UNITED STATES PATENT OFFICE.

CHRISTOPHER B. MICHEL, OF OILFIELDS, CALIFORNIA.

QUICK-ACTING RETAINER FOR DEMOUNTABLE RIMS.

1,212,379.

Specification of Letters Patent. Patented Jan. 16, 1917.

Application filed April 10, 1916. Serial No. 90,030.

To all whom it may concern:

Be it known that I, CHRISTOPHER B. MICHEL, a citizen of the United States, residing at Oilfields, in the county of Fresno, 5 State of California, have invented certain new and useful Improvements in Quick-Acting Retainers for Demountable Rims; and I do declare the following to be a full, 10 clear, and exact description of the same, reference being had to the accompanying drawings, and to the characters of reference marked thereon, which form a part of this application.

This invention relates to improvements in 15 retainers used for fastening demountable rims to the felly of motor vehicle wheels, and is designed as a quick acting retainer which is not held in place by the use of bolts, nuts or screws as is now the common 20 practice but is held by a wedge structure which is extremely easy of being applied to or removed from the rim. Where bolts and nuts are used there is a great deal of work required to unfasten each retainer and to replace the same and often this form of retainer becomes loose and must be retightened at various times. By the use of my improved retaining members these are simply placed under the rim and spring pressed 25 30 wedges then allowed to engage same and with the centrifugal motion of the wheels these wedges will at all times move tighter with no tendency to loosen unless purposely loosened in order to remove the rim. The 35 wedges are quickly and easily removed from the retainers by means of a tool especially adapted for the purpose and an entire set of retainers can be released from a rim in a very few seconds.

40 A further object of the invention is to produce a simple and inexpensive device and yet one which will be exceedingly useful for the purposes for which it is designed.

These objects I accomplish by means of 45 such structure and relative arrangement of the parts as will fully appear by a perusal of the following specification and claims.

In the drawings similar characters of reference indicate the corresponding parts in 50 the several views.

Figure 1 is a side elevation of a portion of a vehicle wheel showing a rim held in place by means of my improved retainers. Fig. 2 is a sectional view taken on a line X—X of 55 Fig. 1 with the wedge removing tool shown in position. Fig. 3 is a side elevation of

the retainer box showing the retainer there-in. Fig. 4 is a front view of the same. Fig. 5 is a plan view of the wedge removing tool.

Referring now more particularly to the characters of reference on the drawings, the numeral 1 designates the felly of the wheel and the numeral 2 the demountable rim.

My improved retainer comprises primarily a receiving box 3 having a securing bolt 4 by means of which the box 3 is secured to the felly 1, the said box 3 also having a reinforced plate 5 which extends underneath the felly and forms a brace or reinforcement for the box 3 and also a point of bearing for the removing tool as will presently appear.

The box 3 is inclosed on all sides, but two of its sides at the upper end, as at 6, are cut away to form a clearance for the dropping of the retaining member as will presently be noted.

The retaining member comprises a beveled body 7 having a projecting wedge 8 arranged to extend between the demountable rim 2 and the fixed rim 2^a on the felly 1. On the upper end of the retainer 7 are projecting pins 9 having downwardly extending finger grips 10 which normally project outside of the box 3 where they may be readily grasped. The wedge 8 is normally held in position between the rims 2 and 2^a by means of a wedge-shaped binding block 11 which engages the retainer 7 and binds between the said retainer 7 and one of the sides of the box 3, it being held normally in such binding position by means of a strong spiral spring 12 interposed between the bottom of the block 11 and the bottom of the box 3.

On the block 11 is a pin 13 which extends through the spring 12 and through the bottom of the box 3, which pin is provided on its outer end with a shoulder or nut 14 spaced normally from the bottom of the box 3.

To release the wedge 8 from engagement between the rims 2 and 2^a I provide a tool 15 having an upwardly projecting end 16 and an elongated slot 17 terminating in a circular opening 18. By means of the opening 18 the tool may be inserted over the nut 14, the pin 13 then being advanced into the slot 17 which is of a lesser width than the diameter of the nut 14, whereupon the nut 14 may be brought into engagement with the tool 15. The end 16 is then brought

into contact with the brace 5 and by exerting downward pressure on the tool 15 this will cause the same to act as a lever against the nut 14 which will pull the pin 13 and block 11 downward against the spring 12 and release the block 11 from the retainer 7. The finger grips 10 are then grasped and the retainer 7 placed within the box 3, the wedge 8 engaging a notch 19 in one side of the box 3 to hold it from getting in the way of the rim 2. The rim 2 can then be readily removed. After the retainer is removed from between the rims and placed within the box 3 and the tool 15 is removed the block 11 will bind against the retainer to prevent its dropping out while the rim is being changed. The nut 14 is held on the pin 13 by means of a counter pin 14^a or other suitable retaining means. The space 6 allows of the dropping of the retainer into the box 3, the pins 9 and grips 10 then projecting adjacent the sides of the box as is apparent.

From the foregoing description it can readily be seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention as defined by the appended claims.

Having thus described my invention what I claim as new and useful and desire to secure by Letters Patent is:

1. A retaining member for demountable rims comprising a box, a wedge arranged to

engage the rim and having a retaining body projecting within the box, and a spring 40 pressed binding member removably arranged between the retaining body and one side of the box, as described.

2. A retaining member for demountable rims comprising a wedge arranged to engage the rim, a tapered retaining body on the wedge, a box into which the retaining body projects, a spring pressed binding block movable in the box back of the retaining body, a pin on the block projecting 45 through the box, and means on the pin for engagement by a tool for pulling the binding block from engagement with the retaining body, as described.

3. A retaining member for demountable 55 rims comprising a wedge arranged to engage the rim, a retaining body on the wedge, a box into which the retaining body projects, finger grips projecting outside of the box, and spring pressed means for frictionally binding the retaining body within 60 the box to hold the wedge against the rim, as described.

4. A retaining member for demountable 65 rims comprising a box disposed adjacent the rim, a spring pressed wedge within the box, a spring pressed binding block within the box, a pin on the block extending through the box provided with an enlarged head, a tapered retaining member within the box engageable by the block, finger grips on the retaining body, and means on the retaining body engageable with the rim, as described.

In testimony whereof I affix my signature.

CHRISTOPHER B. MICHEL.
